UNITED STATES PATENT OFFICE.

CHARLES T. COE, OF KEARNEY, NEW JERSEY.

AUTOMATICALLY-CONTROLLED TURBINE FAN-BLOWER AND DAMPER.

1,282,046.

Specification of Letters Patent. Patented Oct. 22, 1918.

Application filed October 15, 1914. Serial No. 866,763.

To all whom it may concern:

Be it known that I, CHARLES T. COE, a citizen of the United States, and resident of Kearney, in the county of Hudson and State 5 of New Jersey, have invented certain new and useful Improvements in an Automatically-Controlled Turbine Fan-Blower and Damper, of which the following is a specification.

10 This invention relates to an automatically controlled turbine fan blower and damper. It has for its object the production of a device whereby the draft for the furnace of a boiler is automatically controlled, by the 15 steam pressure of the boiler. The speed of rotation of the fan varies with the steam pressure to be maintained, increasing when the steam falls below a predetermined point and decreasing when the steam pressure 20 rises above said point. The damper is controlled simultaneously with the fan blower by the steam pressure in the boiler.

Figure 1 shows a front elevation of an exemplification of the invention; Fig. 2 represents a right hand side view and section of Fig. 1 on the line 2, 2; Fig. 3 is a top plan view and section of Fig. 1 on the line 3, 3; Fig. 4 is a partial section of Fig. 2 on the line 4, 4; Fig. 5 is a section as on the line 30 5, 5 of Fig. 4; Fig. 6 is a partial plan view and section of Fig. 4 as on the line 6, 6, and Fig. 7 shows a partial enlarged section of Fig. 2 on the line 7, 7.

The invention is shown incorporated with 35 my turbine fan blower, fully described in my patent application Serial Number 846,604 filed June 22nd, 1914. The turbine fan blower is here shown with the casing 20. Nozzle supports 24, 25, 26, respectively with the 40 lugs 27, 28, 29 are formed with said casing. Valves 30, 31, 32 are respectively provided for the said nozzle supports. An exhaust pipe 37 and a safety valve 38 are connected to the lower portion of the casing 20. A 45 fan wheel 40 is supported, on the shaft 42 of the turbine fan blower. An air duct 43 is connected to the casing 20 and extends through the wall 44 of the ash pit of a furnace. So far the description covers the

main elements described in my patent application Serial Number 846,604 aforesaid.

Piping 50, 51 and 52 respectively extends from the lugs 27, 28 and 29. A valve casing 55 is supported on a bracket 56 which extends from the casing 20. Ports 57, 58 and 59 are formed in the valve casing 55 and which have respectively connected thereto the piping 50, 51 and 52. A fluid or steam inlet pipe 60 is connected to the casing 55. A rear head 62 and a front head 63 are connected to the valve casing 55. A stuffing box with the gland 64 is provided for the head 63. A valve spindle 68 extends through the stuffing box of the head 63 and carries the oscillating valve 70 having the 65 triangular port 71, which coacts with the ports 57, 58 and 59.

A bracket 73 is bolted to the wall of the casing 20 and supports a pressure cylinder 74 (preferable hydraulic) which latter is 70 provided with plug piston 75. A cup leather packing 76 is fastened to the lower end of the said piston 75 by means of the screw 77. A lug 78 extends from the upper end of said piston. An arm 80 has one end fastened to 75 the valve spindle 68 and its other end is pinned by means of the pin 81 to one end of the connecting rod 82. The other end of said connecting rod is pinned to the lug 78 by means of the pin 83. A weight 85 is 80 formed with the connecting rod 82.

Bearings 88 and 89 are formed with the duct 43. An oscillating damper shaft 90 has one end supported in the bearing 88 and its other end is supported in a sleeve 91, 85 which latter in turn is supported in the bearing 89.

A pair of hubs 96 and 97 are fastened to the shaft 90 and are formed with the damper wing 98. A hub 99 is fastened to the 90 sleeve 91 and a hub 100 is loosely mounted on the shaft 90. A damper wing 101 is formed with the hubs 99 and 100. An arm 105 has one end fastened to the shaft 90 and an arm 106 has one end fastened to the 95 sleeve 91. Lugs 107, 108 are formed with the duct 43 and support a slide bar 109 with the cross member 110 and bifurcated end

111. Two pairs of links 112, 113 respectively connect the cross member 110 with the arms 105 and 106. A bracket 120 is fastened to the casing 20 and supports a bell 5 crank with the arms 121, 122. The arm 121 has an opening 123 and a pin 124 extending through the bifurcated end 111 engages said opening 123. The arm 122 of said bell crank has a bifurcated end 125 with the elongated 10 openings 126. The bifurcated end 125 straddles the connecting rod 82 and a pin 127 in said rod extends through the elongated openings 126. A cover 130 is bolted to the outer surface of the duct 43 to protect the 15 arms 105, 106, slide bar 109 with their appurtenances.

A hydraulic pressure regulator is indicated in its entirety at 135. Its essential elements are a chamber 136, with a dia- 20 phragm from which latter extends a lug 137. An arm 138 is pivoted at one end on the pivot 139 and it carries a movable weight 140. A three ported valve has coacting therewith the water inlet pipe 141, the water 25 overflow pipe 142 and water regulating pipe 143. The latter pipe is connected to the lower end of the cylinder 74. A steam pipe 145 is connected to the chamber 136.

The operation of the automatically con- 30 trolled turbine fan blower and damper may be recited, by considering the movable parts located as shown in the drawings. The steam in the boiler may be considered much above its normal pressure, and the 35 valve 70 positioned to cover all the ports 57, 58 and 59, by virtue of which steam supplied by the pipe 60, and piping 50, 51 and 52 to all the nozzle supports 24, 25 and 26 is cut off. After the steam has dropped be- 40 low its normal pressure, water is allowed to pass through the regulator 135 and it enters the cylinder 74 through the pipe 143. Thereby the piston 75 rises and the valve 70 swings in the direction of the arrow A, 45 and the ports 57, 58 and 59 are consecutively uncovered, and whereby steam is admitted to the turbine consecutively through the nozzle supports 24, 25 and 26. This causes the fan wheel to start rotating and gradually 50 increase in speed, while said ports are consecutively uncovered. At the same time, the coaction of the connecting rod 82 and damper wings 98 and 101 gradually open the latter with the increased speed of the fan 55 40, so that an increased forced draft is produced, until a predetermined normal pressure is obtained. The speed of the fan wheel 40 and the positions of the damper wings 98 and 101 will then be controlled by steam 60 pressure in the boiler, the fan wheel 40 de- 65 creasing in speed and the said damper wings gradually closing, should the steam pressure rise too high. It will thus be seen that the coaction of the steam pressure with the

turbine automatically maintains the fan 65 wheel 40 at the proper speed and the damper wings 98 and 101 at the proper in- clination to maintain a predetermined pres- 70 sure in the boiler, and which predetermined pressure depends upon the position of the weight 140.

With the novel construction of the connections between the connecting rod 82 and damper wings 98 and 101, when the slide 75 bar 109 moves in the direction of the arrow B, the said damper wings swing in the di- rections of the arrows C to collapse. That is to say the outer ends of said wings swing away from the fan wheel 40 when they col- 80 lapsed to increase the draft through the duct 43. With this construction the damper wings 98 and 101 can be located very close to the fan wheel 40, without one interfering with the other.

Having described my invention what I de- 85 scribe to secure by Letters Patent and claim is:

1. In an apparatus the combination of a turbine, a valve to supply a driving fluid to the turbine, a fan wheel connected to the 90 turbine, a duct for the fan wheel, a pair of damper wings hinged in the duct, means to control the revolutions of the turbine with the coaction of the pressure of the driving fluid, and additional means coacting 95 with the first means and with the pressure of the driving fluid to control the positions of the damper wings.

2. In an apparatus the combination of a turbine, a valve to supply a driving fluid to 100 the turbine, a fan wheel connected to the turbine, an air duct for the fan wheel, a damper wing hinged in the duct, means to control the revolution of the turbine coacting with the pressure of the said driving 105 fluid and additional means coacting with the first means and said pressure to control the position of the damper wing.

3. In an apparatus of the character de- 110 scribed the combination of a turbine and fan wheel, an air duct for the fan wheel, a valve to control a driving fluid for the turbine, a pressure regulator, a pressure cylinder, piping connecting the two latter ele- 115 ments, a piston for the pressure cylinder, connections between said piston and said valve, a pair of damper wings in the air duct coacting with the fan wheel, and means connecting said connections and said damper wings.

4. In an apparatus of the character de- 120 scribed the combination of a turbine, a fan wheel driven by the turbine, an oscillating valve to supply a driving fluid to the tur- 125 bine, a duct for the fan wheel, an oscillating damper shaft extending through said duct, a damper wing fastened to said shaft, a sleeve movably supported on said shaft, a

second damper wing fastened to said sleeve, an arm fastened to said sleeve and an arm fastened to said shaft, a link pinned to each arm, a slide bar pinned to the other ends of 5 said links, a pressure cylinder, a piston in said cylinder, connections between said piston and said valve, and other connections between said connections and said slide bar.

Signed at the borough of Manhattan, in the county of New York and State of New York this 3rd day of October, A. D. 1914.
